UNITED STATES PATENT OFFICE.

FRITZ DÜRR, OF BERLIN, GERMANY.

FRICITION-GEARING.

SPECIFICATION forming part of Letters Patent No. 619,152, dated February 7, 1899.

Application filed April 15, 1898. Serial No. 677,716. (No model.)

To all whom it may concern:

Be it known that I, FRITZ DÜRR, a subject of the Emperor of Germany, and a resident of Berlin, in the Kingdom of Prussia and Empire of Germany, have invented certain new and useful Improvements in Friction-Gearing, (for which I have filed applications for Letters Patent in Germany, dated September 18, 1897; in Denmark, December 10, 1897; in Sweden, December 10, 1897; in Hungary, December 15, 1897, and in Norway, December 15, 1897, and for which I have obtained Letters Patent in Great Britain, No. 29,604, dated December 14, 1897, and in France, No. 270,196, dated April 16, 1898;) and I do hereby declare that the following is a full, clear, and exact description thereof, reference being had to the accompanying drawing, and to the letters of reference marked thereon, which forms part 20 of this specification.

My invention relates to a friction-gearing which can alternately be put into connection with two different power-transmitting mechanisms.

25 My improvement comprises a large friction-wheel having three peripheral flanges providing two outer friction-flanges and a double friction-flange located intermediate of the outer friction-flanges and a divided friction-wheel having friction-flanges adjustable with relation to the double friction flanges of the large friction-wheel, as hereinafter described and claimed.

In order that my invention may be fully 35 understood, I will proceed to describe it with reference to the accompanying drawing, which shows a diametric section of my improved friction-gearing.

30 *a* is a large friction-wheel formed with three peripheral flanges providing two outer friction-flanges *b* of equal diameter and an intermediate double friction-flange *c*.

g is a shaft on which is mounted a divided 45 friction-wheel, consisting of two members *d* and *e*, capable of being shifted to or from each other. These halves are each provided on the inner side with a friction-flange *m* and on the outer side with a friction-flange *n*. The frictional half-wheel *d* possesses a broad

bush-shaped nave *f* and can be moved along 50 the shaft *g*, but not revolubly adjusted, and is provided with a regulating-ring *z*. The half-wheel, with its nave *s*, is movably adjusted on the nave *f*. The moving to and from each other of the two half-wheels *d* and *e* is accomplished by means of two forked 55 levers, of which each is on one side, in connection with a shipper-ring *h*, working in the groove of the regulating-ring *z*, and the other with a shipper-ring *h'*, working in the groove 60 of the nave *s*. In the drawing these forked levers are only shown by dotted lines and oscillate about the pivot-points *i*, so that if the half-wheels *d* and *e* are moved toward each 65 other both their friction-flanges *m* bind on the double friction-flange *c* of the friction-wheel *a* and one of the transmission ratios steps into action. If, however, it is desired to operate the other transmission ratio, then both half-wheels *d* and *e* are shifted so far asunder that 70 the friction-flanges *n* of the half-wheels *d* and *e* bind on their respective friction-flanges *b* of the friction-wheel *a*.

If the gearing is to be placed entirely out of gear, the half-wheels *d* and *e* are shifted to 75 such an extent that they will not bind on the friction-flanges *b* nor the double friction-flange *c*.

Having thus described my invention, the following is what I claim as new therein and 80 desire to secure by Letters Patent:

1. A friction-gearing comprising a friction-wheel having three peripheral flanges providing outer friction-flanges and a double friction-flange located intermediate of the outer 85 friction-flanges, a divided friction-wheel having members provided with inner and outer friction-flanges, and means whereby the members of the divided friction-wheel are adjusted with relation to the friction and double friction flanges of the other friction-wheel; substantially as described.

2. A friction-gearing comprising the wheel *a* having the friction-flanges *b* and projecting double friction-flange *c*, the divided friction-wheel having one member *d* provided with a nave *f*, a regulating-ring *z*, an inner friction-flange *m*, an outer friction-flange *n*, and an

other member *e* provided with a nave *s*, an inner friction-flange *m* and an outer friction-flange *n*, and means whereby the members of the divided friction-wheel are adjusted with relation to the friction and double friction flanges of the other friction-wheel; substantially as described.

The foregoing specification signed at Berlin this 30th day of March, 1898.

FRITZ DÜRR.

In presence of—
W. MOCK,
C. H. DAY.
